UNITED STATES PATENT OFFICE.

FRED G. MCWER, OF ANTRIM, NEW HAMPSHIRE, ASSIGNEE TO GOODELL COMPANY, OF ANTRIM, NEW HAMPSHIRE, A CORPORATION OF NEW HAMPSHIRE.

FRUIT AND VEGETABLE SLICER.

1,107,695.

Specification of Letters Patent. Patented Aug. 18, 1914.

Application filed May 4, 1911. Serial No. 624,906.

To all whom it may concern:

Be it known that I, FRED C. MOWER, a citizen of the United States, residing at Antrim, county of Hillsboro, State of New Hampshire, have invented an Improvement 5 in Fruit and Vegetable Slicers, of which the following description, in connection with the accompanying drawing, is a specification, like letters on the drawing representing like parts.

This invention relates to a slicer adapted for slicing fruits or vegetables and has for its object to provide a simple slicer which has a novel automatic feed which will automatically and yieldingly feed the article to be sliced against the slicing knife and which has a novel construction by which the feeding means can be rendered inoperative or held out of operation, and which has 20 other features of improvement, all as will be more fully hereinafter described and then pointed out in the appended claims.

Referring to the drawings wherein I have shown a selected embodiment of the invention, Figure 1 is a side view of the slicer showing it clamped to a table, shelf or other support; Fig. 2 is a top plan view of the slicer; Fig. 3 is a section on the line $\alpha-\alpha$, Fig. 2; Fig. 4 is a section through the slicing knife; Fig. 5 is an end view of the slicer looking toward the right, Fig. 1; Fig. 6 is a section on the line $y-y$, Fig. 1; Fig. 7 is a detail of the locking means for the follower.

My improved slicer comprises a frame 1 which is herein shown as being provided with a clamp 4 of some suitable construction by which it may be clamped to a table or other support 5, said frame being provided with a table 2 on which the article 3 to be sliced is supported. The frame is provided with bearings 6 in which is rotatably mounted a shaft 7 that extends longitudinally of the table at one side thereof and 45 that carries at one end a rotary slicing member of some suitable construction. The slicing member herein shown comprises a plurality of slicing blades 8 carried by a hub 30 that is mounted on the shaft 7 and a 50 guard plate or disk 9 also carried by said shaft and having openings 10 adjacent the blades 8. The blades and guard plate can be adjusted relative to each other thereby to vary the thickness of the slice, and this is 55 herein accomplished by making the guard

plate 9 adjustable longitudinally of the shaft. As seen in Fig. 4 the end of the shaft is screw-threaded at 31 and an adjusting nut 32 is screw-threaded onto the shaft and abuts against the hub 33 of the guard plate. 60 A set screw 34 holds the hub and guard plate in adjusted position. The thickness of the slice is determined by the space between the guard plate 9 and the blades 8 and the adjusting nut 32 provides a means for securing an accurate and minute adjustment of the guard plate. In operation the article 3 to be sliced is held against the guard plate 9 and as the blades rotate they cut slices from the article 3 and these slices are ejected 70 through the openings 10.

The table 2 has associated therewith a guiding flange 11 which extends from one edge thereof and which assists in holding the article 3 in proper position. The article 75 is forced toward the slicing member by means of a follower 12 which is herein shown as slidably and pivotally sustained by the shaft 7. For this purpose the follower is formed with the boss or bearing 13 80 through which the shaft loosely extends. This permits the follower to be swung from its operative position shown in full lines Fig. 3 to its inoperative position shown in dotted lines in said figure, and also to be 85 moved back and forth over the table 2. The follower has connected thereto a flexible connection 14 which is wound around and is secured to a pulley 15 that is loosely journaled on a stud 16 extending from the frame 90 1. This stud is encircled by a spring 17 one end of which is fastened to the stud as at 18, and the other end of which is secured to the pulley 15, as at 19, so that the spring tends normally to turn the pulley 15 in a 95 direction to wind up the cord or flexible connection 14 thereon. This spring and cord thus constitute automatically-operative means tending to force the follower toward the slicing member. The face of the follower is preferably provided with projections 100 20 which engage the article 3 to be sliced.

In operating the device, the follower 12 is pulled backwardly sufficiently to permit 105 the article to be placed on the table between it and the slicing member, and when the follower is released the spring 17 acts to force the follower forwardly against the article 3 and to move the article against the 110

guard plate 9. The article may then be sliced by simply rotating the shaft 7, said shaft being provided with a crank handle 21 for this purpose. During the slicing operation the operator is not required to give any attention to the feeding of the article 3, for the spring 17 will automatically feed the article so that all the slices which are cut will be of the same thickness.

10 The bearing 6 at the left-hand end of the frame in Figs. 1 and 2 limits the feeding movement of the follower and thus prevents it from coming into position to be struck by the knives.

15 In the present embodiment of my invention the table 2 is in the form of a piece of sheet metal secured to the arms 23 extending from the frame, and this sheet metal is bent up at one edge to form the guiding flange 11. The frame is provided with a notch 24 near the right-hand end and the boss 13 of the follower is provided with a locking finger 25 which is adapted to enter said notch when the follower is swung about 20 the shaft 7, see dotted lines Fig. 3. When it is desired to lock the follower in its retracted position, said follower may be withdrawn into such retracted position and then swung about the shaft 7 to cause the finger 25 to 25 enter into the notch 24.

30 My device it will be seen is extremely simple and can be easily operated.

Having fully described my invention, what I claim as new and desire to secure by 35 Letters Patent is:—

1. In a fruit and vegetable slicer, the com-

bination with a frame having a table to support the article to be sliced, of a shaft journaled in the frame and extending longitudinally of the table, a rotary slicer sustained by the shaft at the end of the table, and a spring-pressed follower slidably mounted on the shaft and also adapted to turn thereabout, said frame having a notch, a finger on the follower adapted to enter 40 said notch when the follower is turned about the shaft away from the table, said notch being situated to lock the follower in 45 its retracted position.

2. In a fruit and vegetable slicer, the combination with a frame having a table to support the article to be sliced and provided with a flange depending from the table, of a shaft journaled in the frame adjacent to said flange, a rotary slicer sustained by the 50 shaft at the end of the table, a spring-pressed follower slidably mounted on the shaft and also adapted to turn thereabout, said flange having a notch and a finger 55 rigid with the follower and adapted to enter said notch when the follower is turned about its shaft away from the table, said notch being situated to lock the follower in its retracted position.

In testimony whereof, I have signed my 60 name to this specification, in the presence of two subscribing witnesses.

FRED G. MOWER.
